UNITED STATES PATENT OFFICE.

THOMAS D. DICKINSON, OF NEWCASTLE, INDIANA.

VOLATILE-LIQUID BURNER.

1,147,617.

Specification of Letters Patent. Patented July 20, 1915.

Application filed January 30, 1915. Serial No. 5,285.

To all whom it may concern:

Be it known that I, THOMAS D. DICKINSON, a citizen of the United States, residing at Newcastle, in the county of Henry and State of Indiana, have invented certain new and useful Improvements in Volatile-Liquid Burners; and I do hereby declare the following to be a full, clear, and exact description of the invention, such as will enable others skilled in the art to which it appertains to make and use the same.

This invention relates to burners for utilizing volatile liquid for heating purposes, and the primary object of the invention is to provide a burner as specified which has a novel form of air mixer associated therewith, for properly mixing the air and the volatile gases to insure the proper combustion of the same.

Another object of the invention is to provide a mixer which will feed air to the gas, transversely of the direction of travel of the gas.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a side elevation of the improved volatile fuel burner, Fig. 2 is a vertical sectional view through the burner, Fig. 3 is a plan view of one of the air baffle plates, and Fig. 4 is a detail enlarged sectional view through the mixer of the burner.

Referring more particularly to the drawings, 1 designates the supporting base of the burner, which is preferably circular in plan, but it may be made in any desired shape. The base 1 has depending legs 2 formed thereupon, for supporting the same above a permanent support.

A transversely extending top or upper end 3 of the supporting base 1 has a volatile fuel retaining tank 4 connected thereto, to the upper surface of which is secured a wick retaining sleeve 5. The wick retaining sleeve 5 is secured to the central portion of the top of the volatile fuel retaining receptacle 4.

The sleeve 5 has a wick guiding sleeve 6

positioned centrally therein, which sleeve extends downwardly through the receptacle 4 and communicates with the atmosphere underneath the bottom of the receptacle, as is clearly shown in Fig. 2 of the drawings. A tubular capillary wick 7 is positioned between the sleeves 5 and 6 and extends downwardly into the interior of the receptacle 4.

The sleeve 5 has a mixer 10 removably mounted upon its upper end, which mixer comprises a pair of horizontally disposed disks 11 and 12, which are connected to each other by means of tubes 13. The disk 12 has a depending sleeve 14 formed thereupon which encompasses the upper end of the sleeve 5 and lies in frictional engagement therewith for preventing the accidental movement of the sleeve 14 upon the sleeve 5. The disk 11 is provided with an opening 15 extending centrally therethrough, which provides for the products of combustion to pass upwardly through the disk and into a tubular flue 16. The tubular flue 16 is illustrated in the drawings as being composed of a plurality of connected lengths of metallic tubing, but it is to be understood that the same may be constructed of a single piece if it is so desired or any number of lengths of tubing, without departing from the spirit of this invention. The lowermost section 17 of the tubing 16, has radially extending tongues 18 formed upon the lower end thereof, which tongues lie in engagement with the upper surface of the disk 11, and are bent over the periphery of the disk and into engagement with the lower surface of the same, for securely holding the section 17 of the flue connected to the baffle disk 11.

A housing 20 is supported by the base 1 and extends upwardly about the wick carrying tube, the mixer and the flue 16. The housing 20 is provided with circumferentially spaced perforations 21 formed in the upper and lower ends of the same, which perforations permit of the inlet of the proper amount of air into the interior of the casing to insure the proper combustion of the volatile fuel fed upwardly by the capillary wick 7. The housing 20 has a substantially rectangular shaped opening 22 formed in the side thereof, which has substantially U-shaped guideways 23 arranged along the vertical marginal edges of the same, in which guideways is slidably seated a door 24. The door 24 forms a closure for the opening 22, and when in an open position

2
permits of the igniting of the volatile fuel as it passes upwardly from the upper end of the wick 7, into and between the baffle plates 12.

- 5 Any suitable type of mechanism for raising or lowering the wick 7 may be employed, and also any suitable type of means may be employed for forming a closure for the inlet opening 25 of the receptacle 4.
- 10 In the operation of the improved volatile fuel burner: The receptacle 4 is first filled with any desired type of volatile fuel, which fuel is fed upwardly through the wick 7, to the upper ends of the sleeves 5 and 6.
- 15 The wick 7 is then adjusted so that its upper end will extend a short distance above the upper ends of the sleeves 5 and 6. When the fuel is ignited, at the upper end of the wick 7, the proper combustion of the same 20 will be insured by air mixing with the fuel, between the horizontally disposed disks 11 and 12. Further air will be fed upwardly for mixture with the fuel, through the sleeve 6, which will insure of the proper mixture of 25 air and volatile fuel to insure the proper combustion and best results from the fuel used.

From the foregoing description taken in connection with the accompanying drawings the advantages of construction and the 30 method of operation of the improved volatile burner will be readily apparent to those skilled in the art to which this invention appertains and, while in the foregoing de-

scription, the principle of the operation of this invention has been described together with various features of construction, it is to be understood that certain minor features of construction, combination and arrangement of parts may be altered to suit 40 practical conditions provided such alterations are comprehended within the scope of what is claimed.

What is claimed is:—

In a burner for volatile fuel, a supporting 45 base, a volatile fuel retaining tank carried by said base, a wick sleeve secured to and extending upwardly from the upper surface of said receptacle, a wick guiding sleeve extending through and upwardly from said 50 receptacle interiorly of said retaining sleeve, said guiding sleeve having communication with the atmosphere beneath said receptacle, a capillary wick positioned between said sleeves and extending into said receptacle, 55 a pair of horizontally disposed spaced disks detachably connected to the upper end of said wick guiding sleeve, a tubular flue connected to one of said disks and extending upwardly therefrom, and an inclosing housing carried by said supporting base and positioned about said sleeve and said flue.

In testimony whereof I affix my signature in presence of two witnesses.

THOMAS D. DICKINSON.
